WILLIAM S. HAIGHT, OF WATERFORD, NEW YORK.

Letters Patent No. 79,342, dated June 30, 1868.

IMPROVED APPARATUS FOR HOPPING BEER.

The Schedule referred to in these Letters Patent and making part of the same.

TO ALL WHOM IT MAY CONCERN:

Be it known that I, WILLIAM S. HAIGHT, of Waterford, in the county of Saratoga, and State of New York, have invented a new and improved Beer-Hopping Apparatus; and I do hereby declare that the following is a full, clear, and exact description thereof, which will enable others skilled in the art to make and use the same, reference being had to the accompanying drawings, and to the letters of reference marked thereon, forming part of this specification, in which—

Figure 1 represents a vertical longitudinal section of my improved beer-hopping apparatus, taken on the plane of the line $x\ x$, fig. 2.

Figure 2 is a vertical transverse section of the same, taken on the plane of the line $y\ y$, fig. 1.

Figure 3 is a detail side view of a series of hopping-boxes, arranged into one continuous apparatus.

Similar letters of reference indicate corresponding parts.

This invention relates to a new apparatus for hopping beer, and for extracting beer from hops, and consists in the application of a stirrer in the extractor-box, and of suitable pipes for drawing off the liquid, and for preventing its overflow: also in the arrangement of a valve in the lower part of the apparatus, for discharging the spent hops.

A, in the drawing, represents a box, made of wood or other suitable material, of rectangular or other form, and of suitable size. It is provided with an air-tight-closing cover, B, which is removable, and which is held in place by means of bolts $a\ \&\ b$, that are hinged to the body of the box. A portion, C, of the cover may be securely fixed to the box, for the several pipes to pass into or through; thereby the removal of the main part B of the cover is facilitated.

Within the box is arranged a perforated false bottom, D, and a perforated false cover, E, both of which are removable. Between the false bottom and the false cover is arranged a longitudinal shaft, F, which has its bearings in the ends of the box, and which is, on the outside, provided with a crank or pulley, b, by means of which it receives rotary motion.

The shaft should be so arranged that it can be easily lifted out, whenever desired, so as to allow the false bottom to be taken out. Therefore the crank b is secured to a pin, c, which passes through the stuffing-box d in the end of the box, and then into a socket, provided in the end of the shaft. The socket is square or feathered, or otherwise so arranged that the pin c will be locked to the shaft, so as to turn it. By then drawing out the pin c, the shaft will be released at one end, and can then be easily lifted out, as its other end rests in a short, and, if need be, slotted box, e, as is clearly shown in fig. 1.

On the shaft F is mounted a series of suitably-constructed stirrers, f, f, which work through the hops that are held between D and E. Into the cover B, or rather into the fixed part C of the same, enters a supply-pipe, G, through which the liquor to be treated is let into the box.

H is a discharge-pipe. The same enters the box below the false bottom D, as shown.

I is an overflow-pipe, which fits with one end below the false bottom D, and which passes up to the under side of the cover, and then out, either directly into the adjoining box A, as in fig. 3, or into the discharge-pipe H beyond the tap g, arranged therein, as in fig. 1.

J is a pipe, leading from the top of one box to that of the other, to convey the aroma and vapors from one box to another. If only one box should be employed, or even, where a series of boxes is used, it may be found of advantage to let the aroma-pipe J lead into the overflow-pipe I, as is clearly shown in fig. 1. A series of such boxes may be arranged alongside of each other, as in fig. 3, or above each other, or be otherwise arranged in connection with each other.

The hops to be treated are placed upon the false bottom D, and covered by the cover E. Liquor is then introduced through the pipe G, and the stirrer set in motion, while steam is let into the lower compartment through a pipe, K.

The lower compartment may also be heated by means of a worm arranged therein, in which worm steam or other hot liquid is contained.

Through the bottom and false bottom of the box A may be fitted a plug, L, which, when drawn out, allows the discharge of the hops from the box, without requiring them to be taken out from the top. In place of the plug, a tube, M, may be used, as in fig. 2, the said tube being closed by means of a valve, N; that is operated by a lever on the upper part of the box, as shown.

The apparatus should also be provided with a gauge, O, to facilitate the ascertaining of the height of the liquid in the box.

Having thus described my invention, I claim as new, and desire to secure by Letters Patent—

1. Arranging a rotary stirrer, F f, in a hopping-apparatus, between two perforated shelves D and E, substantially as herein shown and described.

2. The arrangement, in a beer-hopping apparatus, of the discharge-pipe H and overflow-pipe L, both arranged substantially in the manner herein shown and described, the overflow-pipe entering the discharge beyond the tap g in the latter, as set forth.

3. A beer-hopping apparatus, consisting of the box A, air-tight cover B, perforated false bottom D, and perforated false cover E of the stirrer F f, discharge-pipe H, overflow-pipe I, and aroma-conducter J, all made and operating substantially as herein shown and described.

4. Making the stirrer-shaft F removable, by suspending one end upon the pin or arbor e of the driving-crank or pulley, substantially as herein shown and described.

5. The application of the plug L, or its equivalent, through the real and false bottoms of the box A, for the purpose of facilitating the discharge of the spent hops, as set forth.

The above specification of my invention signed by me, this 9th day of May, 1868.

WILLIAM S. HAIGHT.
